UNITED STATES PATENT OFFICE.

WILLIAM FRANCIS, OF PHILADELPHIA, PENNSYLVANIA, ASSIGNOR OF THREE-FIFTHS TO FRANCIS MORTON, FRANCIS SCHOMMER, AND THOMAS MORROW, OF MANAYUNK, PHILADELPHIA, PENNSYLVANIA.

WILLOW.

SPECIFICATION forming part of Letters Patent No. 759,362, dated May 10, 1904.

Application filed March 14, 1902. Serial No. 98,213. (No model.)

To all whom it may concern:

Be it known that I, WILLIAM FRANCIS, a citizen of the United States, residing at No. 535 Hermitage street, Roxborough, Philadelphia, 5 State of Pennsylvania, have invented certain new and useful Improvements in Willows, of which the following is a specification, reference being had therein to the accompanying drawings.

10 My invention relates to improvements in the machine technically known as a "willow," in which certain gearing and mechanical movements operate to automatically feed the willow with fiber or other material to be beaten, 15 opened up, and cleaned and to automatically discharge same when cleaned, the object of my invention being to improve said feeding and discharging mechanism by providing better and more economical mechanical movements for said feed and discharge mechanism. 20 This object I attain in the manner hereinafter set forth, reference being had to the accompanying drawings, in which--

Figure 1 is a longitudinal section of the 25 willow. Fig. 2 is a side elevation of same. Fig. 3 is a plan view of the feed mechanism. Fig. 4 is a detail view of the feed mechanism.

The machine known as a "willow" consists of a casing *a*, having appropriate bearings 30 for a transverse shaft *a'*, upon which is mounted a drum *a''*, consisting, usually, of a series of hollow arms with projecting teeth *a'''* at their outer ends, the drum being rotated and the teeth *a'''* of the same co-operating with 35 certain fixed teeth *a''''*, and perforated or slotted segmental screens *a''''* and *a'''* operate to open or loosen up, beat, and remove the dust or dirt from the masses of fiber subjected to the action of the machine. With the machine are 40 usually combined an exhaust-fan *b*, a pair of feed-rolls *c*, a conveyer-belt *d* for carrying the masses of uncleaned fiber to the feed-rolls, and a pivoted discharge-door *f* at the bottom of the machine, through which the cleaned 45 and separated masses of fiber are discharged. The shaft *a'* has the usual driving-pulley *a''* and the pulley *b'* for receiving the belt *b''* to drive the fan *b*. It also has the pulley *c''* to receive the belt *c''* to drive the pulley *c'''*, which

is free to revolve on the stud *c''*, Figs. 3 and 50 4, and has secured to its hub the gear *c''''*, which is in gear with the gear *c'''* of the shaft *c'''*. The stud *c''* is secured in the slot *c''* of the stand *c''''* and is adjustable to permit gears of different diameter being substituted for the 55 gears *c''''* and *c'''* to vary the number of revolutions of the shaft *c'''* for each revolution of the shaft *a'*. The shaft *c'''* has suitable journals which are secured to the casing *a* and carries the bevel-gear *c''''''*, which is in gear with a 60 similar bevel-gear *c'''''''*, secured to the worm *c''''''*, which is mounted in the journals *c''''''* *c'''''''*. The worm *c''''''* is in mesh with the worm-wheel *c'''''''*, secured to the hub of the disk *c'''''''*. The disk *c'''''''* revolves on the stud *c''''*, secured to the casing *a*, and has a segmental rack *c''''''* on its rim. It is also provided with a projecting pin *c''''''* on its outer face. The segmental rack on the disk *c'''''''* moves in a clockwise direction and meshes into the pinion *c'''''''*, secured to the shaft 65 70 of the lower feed-roll *c*. The stated direction of movement of the rotating rack acts to hold the feed-rolls firmly in their bearings and reduces jarring and friction and wholly obviates breakage of the gear-teeth. On the opposite 75 end of the shaft of the feed-roll *c* is secured the gear *c'''''''*, which is in gear with a similar gear *c'''''''*, secured to the shaft of the upper feed-roll *c*. To the shaft of the lower feed-roll *c* is secured the gear *c'''''''*, which is in gear 80 with the follower-gear *c'''''''*, mounted on a suitable stud secured to the casing. The follower-gear *c'''''''* is in gear with the gear *d'*, secured to the driving-shaft of the conveyer-belt *d*.

The discharge-door *f* is secured to the shaft 85 *f'* and is held in the closed position by the weight *f''*. The sprocket-wheel *f'''* is mounted on and free to revolve on the stud *f''*, secured to the casing of machine. The sprocket-wheel *f'''* is secured to shaft *f'* and is connected by 90 sprocket-chain *f''''* with sprocket-wheel *f'''*. Sprocket-wheel *f'''* is provided with the arm *f''''*, which is provided with shoe *f''''''* to make contact with the projecting pin *c'''''''* on the disk *c'''''''*.

h is a relief-valve to admit air into the willow to supply fan *b* when the discharge-door *f* is open and fiber is being discharged. It is connected by the chain *f'''''''* with the arm

f^{12} , secured to the sprocket-wheel f^5 , which is secured to the shaft f' of the discharge-door f , said relief-valve h being opened simultaneously with discharge-door f .

5 In the operation of the machine, the discharge-door f being held in the closed position by the weight f^2 and the relief-valve h being closed, a quantity of fiber is placed on the conveyer-belt d . The worm c^{12} , being 10 rotated through the medium of the pulley c^4 , gears c^6 and c^7 , shaft c^8 , and bevel-gears c^{10} and c^{11} , revolves the worm-wheel c^5 and disk c^{16} in the direction of the arrow, Fig. 2. The segmental rack c^{18} on the disk c^{16} rotates the pinion c^{20} and the lower feed-roll c' 15 in the direction of the arrow, Fig. 2. This motion being downward causes the lower feed-roll to rest firmly in its journals, preventing its raising up and getting out of gear, as in other machines of this class. The gears c^{21} 20 and c^{22} on the opposite ends of the feed-rolls rotate the upper feed-roll and the gear c^{23} on the shaft of the lower feed-roll c through the medium of the idler-gear c^{24} , and the gear d' 25 moves the feed-belt d , carrying the fiber placed thereon to the feed-rolls to be fed into the willow and brought into contact with the revolving teeth a^3 and stationary teeth a^4 to be beaten, opened up, and cleaned, the coarse 30 dirt falling through the screen d^5 to be removed through the door a^{10} , the fine dust or dirt being drawn through the fine screen d^6 by the fan b . The segmental rack c^{18} is of such length as to revolve the feed-rolls a sufficient length of time to introduce into the 35 machine sufficient fiber for a charge. After the segmental rack has ceased to revolve the feed-rolls the pin c^{19} , which is placed at a point in the rear of the segmental rack to allow 40 sufficient time for the fiber fed into the machine to be thoroughly treated, makes contact with the shoe f^{10} on the upper end of the arm

f^7 , attached to the sprocket-wheel f^3 , causing same to revolve on stud f^4 and by means of sprocket-chain f^6 imparting motion to 45 sprocket-wheel f^5 , secured to shaft f' , opening discharge-door f , allowing treated fiber to be discharged. At the same time the chain h of the relief-valve h , being connected to arm f^{12} , is drawn down, opening relief-valve h , admitting air to the fan b to allow a free discharge of dust, &c. The shoe f^{10} is of sufficient length to hold the discharge-door open until the treated fiber is discharged. The operation is completed in one revolution of the disk c^{16} , 55 the time of each revolution being varied by a change of the gears c^7 and c^8 to suit the material being treated.

What I claim, and desire to secure by Letters Patent, is—

The combination of a willow having a discharge-door, a suction-fan, a valve for admitting air to the casing to supply said fan, and means for simultaneously opening the discharge-door and valve, said means comprising 65 a worm, a shaft, a worm-wheel on said shaft in position to engage the worm, a disk on said shaft provided with a projecting pin, a stud, a sprocket-wheel thereon provided with a shoe disposed in the path of said pin, a 70 shaft carrying the discharge-door, and means for maintaining said door closed, a sprocket-wheel on said last-mentioned shaft, a chain connecting said sprocket-wheels, an arm on said last-mentioned shaft, and a flexible connection between said arm and valve, substantially as described.

In testimony whereof I affix my signature in presence of the witnesses.

WILLIAM FRANCIS.
